UNITED STATES PATENT OFFICE.

CHARLES ARELT, OF BROOKLYN, NEW YORK, ASSIGNOR TO INDEPENDENT PAPER MILLS, INC., OF BROOKLYN, NEW YORK, A CORPORATION OF NEW YORK.

DISPENSING CABINET.

Application filed January 17, 1923. Serial No. 613,187.

To all whom it may concern:

Be it known that I, CHARLES ARELT, a citizen of the United States, and resident of the borough of Brooklyn, county of Kings, city and State of New York, have invented certain new and useful Improvements in Dispensing Cabinets, of which the following is a specification.

My invention relates to dispensing cabinets and more particularly to cabinets for dispensing paper napkins, paper towels or equivalent articles and has for its object to provide a cabinet of novel and simple construction adapted to provide for the withdrawal of individual napkins, towels or the like in a unique manner and to provide an efficient protection for said napkins, towels or the like against contamination. Other more specific objects of the invention will appear from the description hereinafter and the features of novelty will be pointed out in the appended claims.

In the accompanying drawings which show several examples of the invention without defining its limits, Fig. 1 is a front elevation of the cabinet; Fig. 2 is a side elevation thereof, partly in section; Fig. 3 is a perspective view of a package of paper napkins arranged for use in the cabinet; Fig. 4 is a cross-section of the cabinet on the line 4—4 of Fig. 2; Fig. 5 is a cross-section on the line 5—5 of Fig. 2; Fig. 6 is a fragmentary, longitudinal section of the delivery end of said cabinet; Fig. 7 is a perspective view of a follower which may be utilized in the cabinet; Fig. 8 is a sectional elevation of another form of the cabinet; Fig. 9 is an inverted plan view thereof and Fig. 10 is an exterior view illustrating the cabinet in position for refilling.

In the form shown in Figs. 1 to 7, inclusive, the cabinet comprises a container 5 of suitable material and of convenient dimensions which has its lower end open and which is provided preferably with brackets or other devices 6 whereby said container may be suspended from a wall or other support 7; the upper end of this form of the container 5 may be open or, as is preferred, it may be permanently closed as indicated at 8. At its lower end the cabinet is provided with a plurality of members 9 which extend inwardly toward each other to provide a support for the contents of the container 5 and to define a space or discharge

opening 10 through which the contents may be removed in individual units. In the preferred construction the cabinet 5 is made in the form of a Greek cross in cross-section and is adapted to contain a stack 11 of napkins, towels or the like which, as shown in Fig. 3, are also arranged in the form of a corresponding cross, the arms of which extend into the channels 12 resulting from the cross-shape of said container as shown in Figs. 4 and 5. In such case the members 9 are located at the lower ends of said channels 12 and are of such dimensions as to practically close the same and to define a rectangular space 10 corresponding in dimensions to the intermediate area *a* of the stack of napkins, towels or the like. A follower or weight 13 also of cross-shape has its arms slidably fitted in the channels 12 and is adapted to rest upon the stack 11 to exert a downward pressure thereon. Because of the fact that alternate napkins, towels or the like cross each other at the intermediate section *a* of the stack, this intermediate section is of greater density than the projecting portions of said stack. The weight of the stack plus the pressure exerted by the follower or weight 13 tends to bulge the intermediate section *a* of the lowermost napkin downwardly through the discharge space 10 so that the edges of said terminal napkin are readily accessible and easily taken hold of when it is desired to secure a napkin, towel or the like. As the terminal napkin is thus withdrawn, the next succeeding napkin immediately takes its place and is likewise bulged downwardly through the opening 10. It will be understood that the napkins, towels or the like are folded in any convenient manner to produce a cross-shaped stack in the most desirable way. In the form shown in Figs. 1 to 7, inclusive, the members 9 are pivoted at 9^a and are fixed against outward movement materially beyond their horizontal positions relative to the container 5, by lugs or stops 14 which extend inwardly at the lower end of the container 5 and provide supports upon which said members 9 are adapted to rest as shown in Fig. 6. Springs 9^b may be provided for automatically and resiliently maintaining said members 9 in their normal positions against said flanges and for returning them thereto. With this arrangement the container 5 may be filled by way of its lower

end; that is to say, the stack of napkins in proper position to register with the channels 12 may be pressed upwardly against the members 9 which are thus forced inwardly 5 against the tension of the springs 9^b and permit the stack 11 to be passed into the container 5. The stack is inserted to a sufficient extent to bring its lowermost end high enough to release the members 9 which are 10 immediately restored to their normal approximately horizontal positions by the action of the springs 9^b. The stack 11 is then lowered and brought to rest upon said members 9 which support the same and are held 15 against outward movement by the action of the flanges 14. It will, of course, be understood that the follower 13 is introduced either concurrently with the stack or prior thereto as desired. The refilling of the 20 cabinet is thus a very simple operation and makes it possible to permanently seal the upper end thereof from which it follows that a maximum protection against contamination of the napkins, towels or the 25 like is secured. It will be obvious that instead of having the lower end of the cabinet 5 extend in a curve as shown in Fig. 2 of the drawings the same may be otherwise arranged, the curved form being included 30 simply to render the discharge end of the cabinet more accessible.

In the form illustrated in Figs. 8, 9 and 10 the cabinet comprises a container 5^a which generally may correspond as to material, dimensions and form to the container 5 of the form first described. Instead, however, of having its upper end freely open or 35 permanently closed said container 5^a is provided with a cover 8^a hinged at 8^b and having an upstanding lug 8^c provided with an aperture, the purpose of which will appear more clearly hereinafter. Instead of having 40 spring pressed members at its lower end as in the first form, the container 5^a is provided with fixed members 9^c which extend inwardly toward each other to form a discharge opening or space 10^a corresponding to the opening 10 of the form previously described; the members 9^a are located at the 45 lower ends of the channels 12^a of the container 5^a and preferably have their inner ends curved downwardly as indicated at 9^d; if desired two or more of the members 9^c may be provided with recesses as indicated 50 at 9^e for the accommodation of the fingers to facilitate the removal of terminal napkins. In the form now being described the follower 13^a, which may correspond to the follower 13 of Fig. 7, and similarly fit into 55 the channels 12^a, is preferably attached by means of a chain 15 or its equivalent to the cover 8^a whereby the downward movement of said follower and its effect upon the stack of napkins or the like, located in the 60 container, is arrested at a predetermined point.

Instead of being provided with brackets for attachment to the wall or other support, the container in the present form is preferably hinged at its lower end at 6^a to said wall or support so as to be capable of being swung 70 to the horizontal position for refilling as indicated in Fig. 10. To maintain the container in an upright position and at the same time to lock the cover against opening, a staple 16 may be fixed upon the wall or 75 other support 7^a in a position to project through the aperture of the lug 8^c; as shown in Fig. 8 a lock 17 may be hung in the staple 16 to prevent the cover from being opened and the container from being swung on the 80 hinge 6^a out of its upright position. A stop 18 of rubber or other suitable material may be located upon the wall or other support 7^a to form a buffer for the container 5^a and to compensate for the hinge 6^a at the other 85 end of the container whereby the latter is supported in parallel relation to the wall or other support 7^a.

In this form when it is desired to fill the container 5^a it is swung to the position indicated in Fig. 10 in which it may be sustained by means of one or more stop chains 19 and in which the cover 8^a is free to be swung to an open position. The follower 13^a being first removed, the stack of napkins 95 or its equivalent is introduced into the container and brought to rest with one end upon the members 9^c. After having been filled the follower is reintroduced into the container, the cover is closed and the whole device is 100 swung on the hinge 6^a to the position indicated in Fig. 8 and locked therein by means of the staple 16 and lock 17. From this point the operation of the device is exactly 105 the same as in the form previously described, it being understood that the chain 15 is so dimensioned as to permit the follower to travel downwardly to the bottom of the container 5^a. In the preferred arrangement the 110 bottom of the latter is arranged so that the members 9^c are inclined upwardly as shown in Fig. 8; this arrangement is preferred for the reason that in this way the discharge aperture 10^a or in other words the terminal 115 napkin is rendered more easily accessible.

In the preferred form the follower 13 or 13^a is provided with a depending projection 13^b which is adapted to project through the space 10, when the final napkin or its equivalent has been removed, thus indicating that 120 the cabinet is empty; the projection 13^b may be of any desired character but is preferably of a size and shape to fit and approximately fill the opening 10.

The cabinet is particularly designed for 125 containing and dispensing paper napkins and paper towels and by reducing the operation of withdrawing individual napkins or towels to the simplest form, does away with waste which results when individual nap- 130

kins or towels can be obtained only with difficulty; that is to say, the cabinet does away with the possibility of withdrawing more than one individual napkin or towel 5 at a time.

Various modifications may be made without departing from the nature of my invention as set forth in the appended claims.

I claim:

10 1. A dispensing cabinet for sheets of material comprising a container in which said sheets are arranged in a stack, said container having its lower end open, a plurality of members movably connected with said con-

15 tainer and extending toward each other at said lower end to define an opening through which said sheets may be individually removed and means for permanently fixing said members against outward movement

20 relatively to said container to provide a support for said stack and for permitting a movement of said members into said container when the latter is empty.

25 2. A dispensing cabinet for paper napkins or the like comprising a container having the form of a Greek cross in cross-section and arranged to contain a stack of paper napkins or the like stacked to form a corresponding cross, said container having 30 its lower end open, a plurality of members pivotally connected with said container at said lower end and each located in a channel formed by an arm of the cross, said members providing a support for the stack 35 of napkins or the like and extending toward each other to define a rectangular opening through which the terminal napkins or the like may be withdrawn, permanently fixed

lugs extending inwardly at the lower end of 40 said container for arresting outward movements of said members without interfering with the inward movements thereof, springs whereby said members are normally pressed in outward directions against said lugs and are permitted to yield inwardly into said 45 container to permit filling of the latter from below and a cross-shaped follower slidably fitted in the channels of said container and adapted to rest upon said stack of napkins or the like.

50 3. A dispensing cabinet for paper napkins or the like comprising a container having the form of a Greek cross in cross-section and arranged to contain a stack of paper napkins or the like stacked to form a corresponding cross, said container having its lower end open, a plurality of members pivotally connected with said container at 55 said lower end and each located in a channel formed by an arm of the cross, said members providing a support for the stack of napkins or the like and extending toward each other to define a rectangular opening 60 through which the terminal napkins or the like may be withdrawn, permanently fixed 65 lugs extending inwardly at the lower end of said container for arresting outward movements of said members without interfering with inward movements thereof during the filling of the container from below, and 70 springs whereby said members are resiliently maintained in their normal position against said lugs and returned thereto.

In testimony whereof I have hereunto set my hand.

CHARLES ARELT.
